UNITED STATES PATENT OFFICE.

ANDREW J. HIGGINS, OF WEST PHILADELPHIA, PENNSYLVANIA.

COMBINATION-TOOL.

No. 866,931.

Specification of Letters Patent.

Patented Sept. 24, 1907.

Application filed February 14, 1907. Serial No. 357,362.

To all whom it may concern:

Be it known that I, ANDREW J. HIGGINS, a citizen of the United States, residing at West Philadelphia, in the county of Philadelphia and State of Pennsylvania, have 5 invented certain new and useful Improvements in a Combination-Tool, of which the following is a specification, reference being had therein to the accompanying drawing.

My invention relates to a combination tool that may 10 be used as a stove lifter, wrench, screw driver, tack puller, tack hammer and can opener.

The object of the invention is to provide a combination tool of this character which is made in a single piece, so that it is strong and durable and comparatively 15 inexpensive.

With the above and other objects in view, the invention consists in the novel construction hereinafter described and claimed, and illustrated in the accompanying drawings, in which,

20 Figure 1 is a side view of my improved combination tool; Fig. 2 is an edge view of the same; and Fig. 3 is a perspective view, showing the improved can opener.

My improved combination tool is formed from a single piece of metal and comprises a handle or lever 1 having 25 a slight longitudinal curvature. At one of its ends 2 it is slightly enlarged and flattened transversely and is formed at a suitable distance from said end on one side with a cylindrical projection 3 adapted to serve as a hammer head. The extreme outer portion of this end 30 of the tool is curved slightly in the opposite direction and is tapered and beveled, as shown to provide a point 4 which may be used as a screw driver, stove lid lifter, scraper, and the like. The opposite end 5 of the handle or lever 1 is slightly enlarged and flattened in a plane 35 at right-angles to that of the end 2. In this portion 5 of the tool is formed a square transverse opening 6 of a size corresponding to the size of a similar shaped end of the shaft of a rotary stove grate, so that the tool may be used as a shaking lever. The extreme outer end of the por-

tion 5 of the tool is formed with a central notch or recess 7 which forms two outwardly projecting arms 8, 9. The recess 7 has its flat opposing side walls 10 diverging so that nuts or bolt heads of different sizes may be inserted between them and wedged therein to permit the tool to be used as a wrench. A square wrench opening 11 is also formed between the inner end of the recess 7 and the wrench opening 6, the opening 11 being similar to the opening 6, but smaller than the same. The arm 8 has its end formed with a V-shaped notch 12 and its outer surface curved, as shown, to permit said arm to be used as a tack puller. The other arm 9 is in the form of a can opener and it is shaped to provide a cutting spur 13 and a notched portion 14 adapted to engage the edge of a can and serve as a fulcrum and a guide. The cutting spur or blade 13 is arranged to one side and beneath the plane of the prongs of the notched portion 14, as clearly shown in the drawings.

From the foregoing description, taken in connection with the accompanying drawings, it will be seen that the tool is of simple, strong and durable construction, so that it may be manufactured at a comparatively small cost and that it is exceedingly effective for a variety of purposes.

Having thus described my invention, what I claim as new and desire to secure by Letters Patent of the United States, is:

A tool of the character described, comprising a hand lever formed at one of its ends with a recess to provide two arms having their flat opposing faces diverging to permit nuts of different sizes to be engaged by the tool, one of said arms being notched and tapered to provide a tack puller, the other of said arms being formed with a notched guide portion and a cutting spur disposed to one side of said guide portion to permit said arm to be used as a can opener, substantially as shown and described.

In testimony whereof I hereunto affix my signature in presence of two witnesses.

ANDREW J. HIGGINS.
